UNITED STATES PATENT OFFICE

CHARLES O. BALL, OF BIRMINGHAM, MICHIGAN, ASSIGNOR TO YELLOW TRUCK AND COACH MANUFACTURING COMPANY, OF PONTIAC, MICHIGAN, A CORPORATION OF MAINE

WINDOW-REGULATOR ADJUSTMENT

Application filed April 20, 1928. Serial No. 271,545.

This invention relates to regulators such as are used for raising and lowering the windows of closed automobile bodies and, more particularly, to an improved arrangement for mounting the regulator to permit vertical adjustment thereof.

It is one of the objects of the invention to provide a mounting for the regulator mechanism, that will facilitate its assembly in the body, and eliminate the necessity for any unusual degree of care in the fitting of parts to effect a tight seal of the customary weather strip.

A further object of the invention is to provide a mounting that will readily permit adjustment as the parts become worn and the weather strip takes a permanent set, without requiring the removal of body trim, to allow access to the securing means.

Other objects and advantages will be apparent from the following specification taken in connection with the accompanying drawings wherein:

Figure 1 is a side elevation of a window mounted in a body for vertical sliding movement, in accordance with the present invention.

Figure 2 is a detail perspective view with parts broken away and shown in section, illustrating the mounting for the regulator.

Figure 3 is a transverse sectional view of a side portion of the body in which the regulator is mounted.

Figure 4 is a sectional view on line 4—4 of Figure 3.

Referring to the drawing, the window regulator therein shown is of a well-known chain type and comprises an endless belt or chain 1, running over a pair of spaced sprocket wheels 2 and 3; the driving sprocket 2 being associated with suitable gear mechanism housed within a casing 4, from which projects a squared shaft 5, for the fastening thereon of an operating handle (not shown), while the sprocket 3 is pivotally mounted on a dependent bar or strap 6, fixed to the housing 4. A lateral stud or pin 7 is carried by the chain for engagement with a slotted plate 8 secured to a channeled member 9, in which the lower edge of a window pane 10, of glass,

or the like, is positioned. It will be obvious that as the sprocket 2 is rotated, the chain will cause the window 10 to be lowered or raised, into or out of a well in the lower portion of the body section. When the stud 5 passes around the curve of the sprocket wheel 2, it will be moved sidewise in the slot of the plate 8 to the position shown in Figure 1 just beyond a center line and will be held at such uppermost limit by the weight of the window.

During periods of inclement weather, when the window is to be closed, it is desirable to seal the opening in the body through which the window slides, against the entrance of water and cold air. For this purpose, there is provided a weather strip 11, preferably of rubber, carried along the lower edge of the window within an extension 12, at one side of the channeled member 9, and which is adapted to seat against the edge 13 of the opening, when the window is raised to its upper limit. The edge 13 may be formed, as shown in the drawing, by turning over and bending upon itself, the upper portion of the exterior sheet metal body covering or sheathing 14.

It will be apparent that the tight sealing action of the window strip depends upon the height at which the regulator mechanism is mounted and its vertical relation with the edge 13. Ordinarily, the proper relation of the parts is to be had only at great labor and painstaking care, in maintaining dimensions within a very close limit and in accurately fitting the several parts. In the event the rubber strip should take a permanent set after a certain period of use, or should other wear occur, a considerable amount of interior trim must be removed to permit access to the regulator mounting, and the parts must be carefully refitted to remedy the condition. In the present case, these disadvantages are eliminated by mounting the regulator in a manner to readily permit its adjustment after the parts are assembled. To this end, there is provided a regulator panel consisting of a vertical side portion 15 and a horizontal top portion 16, which is secured to the customary body posts, and which carries on its

lower side a wooden tacking rail 17, for the usual cardboard base 18, for trimming material, such as mohair, plush, velour, or the like. The gear casing 4 is carried on a mounting plate 19, having at each side thereof a vertically disposed flanged portion 20, at the top of which is a horizontally disposed flange or ear 21. The regulator is suspended from the top 16, by bolts or screws 22, which extend downwardly and have screw threaded engagement with a nut 23, welded, or otherwise integrally secured on the underside of the flange 21. A series of screws or bolts 24, extend through the side portion 15 on the regulator panel and through elongated slots 25 formed in the flange 20, and have screw threaded engagement with clamp plates 26 located behind the flange 20. Rotation of the screws 24, therefore, draws up the respective plates 26 to clamp the flanges 20 between the plates and the side portion 15 and holds the mounting plate and regulator mechanism in a fixed position.

The arrangement thus described allows rapid initial installation without the necessity for close hand fitting. After the regulator and window are loosely held at approximately correct vertical position by the screws 24, the slots 25 permit adjustment of the screws 22, to carry the regulator upwardly until the rubber sealing strip 11 is brought into tight engagement with the edge of the opening, after which the screws 24 may be drawn up to hold the regulator in its adjusted position. Further adjustment may later be made as necessity demands by simply backing up the screws 24 to allow the regulator to be moved vertically upon manipulation of the suspension bolts 22.

40 To firmly hold the lower end of the strap 6, carried by the regulator casing against rattle, and yet accommodate its vertical movement with the casing, a retainer bracket 27 has been provided for attachment to the bottom sill, the bracket being provided with a pair of spring ears or fingers 28, between which the strap extends.

While but one specific embodiment has been illustrated and described, it is to be understood that the invention is not limited to the exact details mentioned, but that various modifications may be made, such as come within the scope of the appended claims.

55 I claim:

1. In combination, a body panel having a side and top, a window regulator located below the top, adjustable suspension elements hanging said regulator from the top, and adjustable locating means associated with said side, adapted to hold said plate in adjusted position.

2. In combination, a panel having a side and a top, a mounting plate for window regulators or the like, adjustable means for sus-

pending the plate from said top and for permitting adjustment thereof for height, and other means associated with the side for holding the plate in adjusted position.

3. In a sliding window construction, a support panel embodying a top and a side, a window lift member to be carried thereby, adjustable suspension means between the top and window lift member to vary the height of the member and fastening means for clamping said member to the side.

4. In a sliding window construction for vehicle bodies or the like, the combination with a supporting panel and a window raising and lowering device, of an adjustable locator for varying the effective position of said device and a fastener for anchoring the device in a positive adjusted position.

5. In a sliding window construction for vehicle bodies or the like, the combination with a supporting panel and a window raising and lowering device, of a fastener on the panel extending loosely through an opening in said device to permit the relative shifting of the position of said device, a part engaged by the fastener to clamp the device in a definite position, and an adjustable shifter between the panel and device to vary their relative position.

6. In a sliding window construction of the character described, the combination with a supporting member and a window lift member, of a fastener connecting said members and loosely engaging at least one thereof to permit a change in their relation, and a shifter device between the members for effecting the shifting thereof.

7. In a sliding window construction of the character described, the combination with a window receiving well, and a regulator concealed within and operable from outside the well, of a connection between the regulator and wall of the well manipulatable from the exterior of the well to adjustably anchor the regulator in place and a shifter device to vary the position of the regulator and also operable from the exterior of the well.

8. In a sliding window construction of the character described, the combination with a window receiving well, and a regulator concealed within and operable from outside the well, of adjustable means accessible from the exterior of the well to vary the position of the regulator as a whole.

9. A sliding window construction of the character described, including in combination, a window receiving well having a side wall and an overhanging top wall, a window lift unit in said well, having side and top flanges, means adjustably connecting the top wall and top flange for varying the height of the lift unit within the well and a connection for fixedly securing the side flange to the side wall to hold the unit in adjusted position.

10. A sliding window construction for ve-

hicle bodies or the like, involving a window
slidable through an opening in a body por-
tion and provided with a sealing strip for
engagement with the edge of the body por-
tion at the opening when the window is
closed, and a lifter regulator carrying the
window, adapted to raise and lower the same,
characterized by an adjustable mounting for
the regulator including a movable part en-
gageable with the regulator to move it bodily
10 to effect contact of the sealing strip with said
edge.

11. A sliding window construction for ve-
hicle bodies or the like, involving a window
15 having a connection with a lift regulator for
raising and lowering the same through an
opening in a body portion, and carrying a
weather strip for engagement with a portion
20 of the body adjacent said opening, when said
connection is at its upper limit, character-
ized by means to adjustably mount the reg-
ulator on the body portion to vary its height
for effecting the tight sealing engagement
25 of the strip and its associated body portion.

26 12. A sliding window construction for ve-
hicle bodies or the like, involving a window
having a connection with a lift regulator for
raising and lowering the same through an
opening in a body portion, and carrying a
30 weather strip for engagement with a por-
tion of the body adjacent said opening, when
said connection is at its upper limit, charac-
terized by means to adjustably mount the reg-
ulator on the body portion to vary its height
35 for effecting the tight sealing engagement of
the strip and its associated body portion, and
means to securely anchor the regulator in ad-
justed position.

In testimony whereof I affix my signature.
